Primary Examiner — Clint A Samuel(74) *Attorney, Agent, or Firm* — Carter, DeLuca & Farrell LLP(57) **CLAIM**

The ornamental design for a lighting apparatus, substantially as shown and described.

DESCRIPTION

FIG. 1 is a perspective view of a lighting apparatus in accordance with the present design;

FIG. 2 is front view of the lighting apparatus of FIG. 1;

FIG. 3 is a rear view of the lighting apparatus of FIG. 1;

FIG. 4 is a right, side view of the lighting apparatus of FIG. 1;

FIG. 5 is a left, side view of the lighting apparatus of FIG. 1;

FIG. 6 is a bottom view of the lighting apparatus of FIG. 1; and,

FIG. 7 is a top view of the lighting apparatus of FIG. 1. The ornamental design which is claimed is shown in solid lines in the drawings. The broken lines shown in the drawings are for the purpose of illustrating portions of the lighting apparatus and form no part of the claimed design.
